(57) **CLAIM**

(21) Appl. No.: **29/105,854**

I claim the ornamental design for top rail for a refrigerated
freight container, as shown.

(22) Filed: **Jun. 1, 1999**

DESCRIPTION

(30) **Foreign Application Priority Data**

Dec. 1, 1998 (GB) 2079528

FIG. 1 is a front/top/right-side perspective view of a top rail
for a refrigerator freight container showing my new design;

(51) LOC (7) Cl. **12-08**

FIG. 2 is a right-side elevational view thereof;

(52) U.S. Cl. **D12/97**

FIG. 3 is a left-side elevational view thereof;

(58) **Field of Search** D23/386, 393;
D9/414, 430-434; 62/406, 371, 407, 239,
420, 384; 220/1.5, 592.09, 592.1; D12/101-104,
97; D25/119, 164

FIG. 4 is a top plan view thereof;

(56) **References Cited**

FIG. 5 is a front elevational view thereof; and,
FIG. 6 is a bottom plan view thereof.

The broken showing is for illustrative purposes only and
forms no part of the claimed design.
